UNITED STATES PATENT OFFICE.

HENRY WIEMER, OF DOW CITY, IOWA.

HORSE-TIE.

1,113,392.

Specification of Letters Patent. Patented Oct. 13, 1914.

Application filed April 12, 1913. Serial No. 760,687.

To all whom it may concern:

Be it known that I, HENRY WIEMER, a citizen of the United States, residing at Dow City, in the county of Crawford, State of Iowa, have invented certain new and useful Improvements in Horse-Ties; and I do hereby declare the following to be a full, clear, and exact description of the invention, such as will enable others skilled in the art to 10 which it appertains to make and use the same.

This invention relates to improvements in safety hitches for stock.

The object of the invention is to provide 15 an improved safety hitch whereby a row of horses positioned in stalls of a stable may be released at the same time by means operable from without the stable thus protecting the animals in case of fire.

20 A further object of the invention is to provide such a safety hitch which will be operable also by means positioned in the stall.

A still further object is to improve the 25 general efficiency and simplify the structure of a device of this character.

With these and other objects in view, the invention resides in the novel combination, 30 formation and arrangement of parts to be more fully hereinafter described and particularly pointed out in the claim hereto appended.

Reference is had to the accompanying drawings wherein similar characters of reference designate corresponding parts throughout the several views, and in which:

Figure 1 is a top plan view of the plurality of stalls provided with the improved stock hitch, Fig. 2 is an enlarged top plan 40 of one of the hitches with the protective casing thereof being broken away, Fig. 3 is a side elevation of the hitch also with the protective cover being broken away, and Fig. 4 is a vertical sectional view on the line 45 4-4 of Fig. 2.

Referring more particularly to the drawings, 10 designates a plurality of stalls and 11 the usual heavy plank on the top of the manger to which the improved hitch A is 50 attached. The hitch comprises a pair of plates 12 and 13 which are fastened to the plank 11 in opposed relation and bolted thereto. These plates and the adjacent portion of the plank are provided with alining 55 rectangular openings 14 through which is

passed the tie bolt 15 having at its free end a suitable harness engaging ring 16 and at its inner end notches 17 adapted to engage the arm 18 of the latch lever 19 which is pivotally secured to the plate 13 adjacent the side opening 14. The latch lever 19 is normally held in engaged relation with the bolt 15 by means of a leaf spring 20 engaging one arm thereof. Positioned on the plate 13 adjacent the opening 14 and in opposed relation to the latch member 19 is a lug 21 against which the bolt 15 has sliding engagement and which serves to prevent rocking of said bolt when pressure is exerted on one side thereof by means of the 65 spring-pressed latch member.

A concaved shield member 23 is secured to the plate 13 in such position as to cover the working parts of the latch. To actuate the latch member 19 a cord 22 is secured to 75 the outer extremity of the free arm thereof and passed through alining bars formed in the bolt and the plank, said cords extending into the stall. In order to provide a means operable from without the stable for 80 releasing all of the horses simultaneously a rod 25 is passed along the line of the stalls and through alined openings 26 of the shield members. Adjustably secured on these rods as by means of set screws 27 are collars 28 85 which are so positioned that longitudinal movement of the rod 25 will cause the collar to ride on the free arm of the latch member 19 and force it downwardly, thus forcing the arm 18 out of engagement with the 90 bolt 15 to release the same.

What is claimed is:

A safety hitch comprising the combination with an attaching member, of a hitch bolt slidably passed therethrough, an angle 95 latch pivoted adjacent the inner end of the bolt, one arm of said latch engaging the bolt to prevent retraction thereof, an actuating bar and a projection on the actuating bar adapted to engage the latch to release the 100 bolt upon movement of said bar and a flexible member secured to the latch for also rocking the same to release the bolt.

In testimony whereof, I affix my signature, in the presence of two witnesses.

HENRY WIEMER.

Witnesses:

HERMAN LAZERUS,
E. G. WIGGINS.
